UNITED STATES PATENT OFFICE.

CHARLES C. CADDEN, OF CLEVELAND, OHIO.

TELEPHONE HOOK-SWITCH.

No. 843,998.

Specification of Letters Patent.

Patented Feb. 12, 1907.

Application filed March 15, 1905. Serial No. 250,233.

To all whom it may concern:

Be it known that I, CHARLES C. CADDEN, a citizen of the United States of America, and a resident of Cleveland, in the county of Cuyahoga and State of Ohio, have invented certain new and useful Improvements in Telephone Hook-Switch, of which the following is a specification, reference being had to the accompanying drawings, which form a part thereof.

My invention relates to electric switches, and more particularly to telephone switch-hooks employed at the subscribers' stations. Its objects are to improve, simplify, and cheapen the construction of such switches; and it consists of such improvements in the details of construction and relative assemblage of the parts as will hereinafter be fully described and claimed. Certain features herein set forth, however, are specifically claimed by Herbert L. Knight in his application, Serial No. 250,232, filed of even date herewith.

The accompanying drawings show my improvements in such detailed forms and assemblage of parts as is now deemed most desirable by me; but changes not requiring the exercise of invention might be made therein by a skilful mechanic without departure from the spirit of my invention as set forth in the claims at the end of this specification.

In the drawings, Figure 1 is a side elevation, partly in section, of my improved switch mechanism as applied to a telephone-subscriber's station-box, preferably a metallic box. Fig. 2 is a similar view, partly in section, on the line 2 2 of Fig. 3, with the pivotal portion of the main operating-lever shown in a different position from that of Fig. 1 and partly broken away. Fig. 3 is a plan view of the parts shown in Fig. 2, but in the positions of Fig. 1. Fig. 4 is similar view with the main portion of the actuating-lever removed and the parts in section on the line 4 4 of Fig. 2. Fig. 5 is a view in elevation of the pivotal end of the removable main portion of the actuating-lever. Fig. 6 is a side elevation of the insulating-base, the pivot-standard, the secondary portion of the actuating-lever, and its spring. Fig. 7 is a plan view of the pivot-standard and the secondary portion of the actuating-lever mounted thereon.

The same character of reference is employed throughout the several figures to indicate similar parts.

My electric switch mechanism is a complete unit of itself and may be applied in any desired way. In the drawings I have shown it as mounted in a box A, adapted for use at 6c a telephone-subscriber's station. For this purpose the operating-lever B is provided at its end, projecting from the box, with prongs b, upon which to hang a telephone-receiver. The box A may be of any suitable material—65 wood or metal—but I prefer to make it of thin metal, as shown.

A block F of non-conducting material constitutes the base of my device, and at its side is a standard D, secured in place by a 70 screw d and dowel-pins d'. Near the top of the standard is a projecting stud-pin E, which serves as a pivot for the operating-lever B, and at its upper corner farthest from the stud-pin is an overhanging lug d², which 75 serves as a stop to limit the movement of the operating-lever.

The operating-lever is made in two parts B and C, the former having the projecting forked end before referred to removable 80 from the pivot E, while the latter is permanently mounted on the pivot and is provided with means whereby it may be connected to the removable portion of the lever. The pivot-pin E has a threaded portion e, which 85 screws into the standard, and a larger shouldered portion e', upon which is mounted the permanent portion C of the lever, and a still removable portion B of the lever and in which larger portion e², upon which is mounted the 90 is formed an annular groove e³.

The pivotal end of the removable portion B of the lever is slotted, as at b, and in this slot is a thin latch b', pivoted on a pin b² and provided with a slot b³, which engages the 95 pivot-pin E at the groove e³, as will be readily understood. The latch is provided with a projection b⁴, which serves as a handle for operating it.

The permanent portion C of the lever extends forwardly from the pivot E and is preferably U-shaped to secure lightness. Its upper arm c lies beneath the lug d² of the standard, and it is provided with a side projecting lug c', which engages a slot b⁵ in the other 100 member of the lever to insure unison of movement therewith. The lower arm c² of this portion of the lever extends considerably in advance of the upper arm and carries a side 105 projecting screw-stud c³, on which is a non-conductive sleeve c⁴.

On the base F is mounted a strong flat

spring G, the free end of which is curved back toward the base and engages the upper arm c' of the lever C, as shown, tending to hold the lever in its normal raised position. Upon the heel of this spring is imposed a series of blocks H of insulating material, and between these blocks are secured the heel ends of contact-springs or switch-arms J, J', J², and J³, which, together with the blocks and the main

5 10 15

spring G, are secured to the base by screws h, surrounded by sleeves h', of insulating material. Projections j, j', j², and j³ from the heel ends of these switch-arms are apertured, as shown, to afford ready means for making

10 15 20

conducting-wire connections.

The switch-arms normally extend horizontally and out of contact except as they may be sprung by the switch-arm J'. This arm is longer than the others, is bifurcated at its free end, and has one of its forks bent up, as shown at j', so that the stud-pin c³ of the lever portion C lies between the two prongs and actuates the arm J' in unison with the lever. The number of these spring switch-arms and 25 the manner of connecting them in circuit may be varied as desired in the use to which my invention may be put.

As previously stated, I have shown it as adapted for use at a telephone-subscriber's station, and in this adaptation the spring-arms J and J', which are normally in contact, as shown in Fig. 2, when the receiver is on the hook, might be included in the signaling-circuit of the telephone system, while the 30 35 arms J² and J³, which are only in contact when the receiver is off the hook and the lever raised, as shown in Fig. 1, might be included in the talking-circuit.

I claim—

40 1. In an electric switch mechanism, the combination of an insulating-base, a standard secured thereto, a U-shaped spring and a series of insulated spring switch-fingers se-

cured upon the top of the base by the same means, a lever pivoted on the standard and 45 engaged by the free end of the U-shaped spring, the lever lying out of the plane of the switch-fingers and having an insulated pin which extends into said plane and engages one of said fingers, substantially as set forth. 50

2. In an electric switch mechanism, the combination of an insulating-base, a series of insulated switch-fingers imposed on the base, a standard secured to the base and a pivot-pin projecting from standard above the 55 heel ends of the switch-fingers, a lever pivoted on said pin extending in the direction of the free ends of said fingers and having a lower member also extending in said direction but out of the plane of the switch-fingers, 60 an insulated pin on said member extending into the plane of and adapted to engage and operate the switch-fingers, and a U-shaped spring secured on the base its free end bowing around the free ends of the switch-fingers 65 and the lower member of the lever and engaging the main portion of the lever near the standard, substantially as set forth.

3. In an electric switch mechanism, the combination of an insulated base, a series of 70 insulated spring switch-fingers imposed on said base, a standard secured to one side of the base, a lever pivoted on said standard out of the plane of said switch-fingers, with an insulated pin on said lever extending into the plane of said switch-fingers one of which is bifurcated at its free end and engages the 75 said insulated pin between its forks substantially as set forth.

Signed at Cleveland, this 11th day of 80 March, 1905, in the presence of two subscribing witnesses.

CHARLES C. CADDEN.
